UNITED STATES PATENT OFFICE.

THOMAS G. HOLT, OF KANSAS CITY, MISSOURI.

FLOOR-SANDING MACHINE.

Application filed June 24, 1924. Serial No. 722,112.

To all whom it may concern:

Be it known that I, THOMAS G. HOLT, a citizen of the United States, residing at Kansas City, in the county of Jackson and State 5 of Missouri, have invented certain new and useful Improvements in Floor-Sanding Machines, of which the following is a specification, reference being had to the accompanying drawings.

10 This invention relates to improvements in floor sanding machines, and more particularly to a device for sanding the edges of the floors next to the base board.

In the ordinary construction of floor sanding devices such as employed for polishing hardwood floors and the like, the construction thereof is such that it is impossible to sandpaper the floor by the use of the device at that part of the floor lying next to the 15 base molding, the structure of the roller and the location thereof in the machine preventing it being moved nearer to the base molding than about four inches. This space must accordingly be hand scraped or sanded, 20 causing the operation to be very expensive and in cases where scraping is resorted to, the band of flooring about the edge of the room when completed is of a different color 25 from the central portion.

30 An important object of this invention accordingly becomes to provide a device which may be employed for sanding this remaining strip of flooring sufficiently close to the base molding so that any remaining will be 35 covered by the usual ogee strip placed at the bottom of the base molding.

35 A further object of the invention is to provide a device of this character which is readily reversible so that it may be employed for sanding either the right or left 40 hand corners of a room.

45 A still further object of the invention is to provide a device of this character which is simple in its construction and arrangement, readily adjustable, durable in service and a general improvement in the art.

50 These and other objects I attain by the construction and arrangement shown in the accompanying drawings wherein for the purpose of illustration is shown a preferred embodiment of my invention and wherein like reference characters designate like parts throughout.

55 In the drawings:—

Figure 1 is a side elevation of a floor sanding machine constructed in accordance

with my invention showing the machine during the operation of shifting the sanding wheel or roll from one side of the machine to the other, the final position of the machine being shown in dotted lines; 60

Figure 2 is a side elevation of the opposite side of the machine; and

Figure 3 is a plan view, parts being broken away and parts being shown in section. 65

Referring now more particularly to the drawings, the numeral 10 designates a motor housing having the base thereof mounted upon supporting rollers 11. Upon the hub portions 12 of the motor housing, or those 70 portions thereof in which the shaft 13 of the motor is journaled, are mounted bushings 14, the hub portions of the housing being preferably turned down to a uniform diameter for the reception of these bushings. 75

The peripheries of the bushings 14 have formed therein grooves 15 which receive tongues 16 formed upon the coacting faces of bearings 17 formed upon the inner ends of connecting rods 18. The connecting rods 18 are adjustable as to length, as by means of bolt and slot engagement, such as indicated at 19, and are provided at their forward ends with bearings 20 which bearings are connected by a housing 21. A shaft 22 is rotatably mounted in these bearings and extends therethrough and through the housing 21, the ends of the shaft projecting beyond the housing and one end of the shaft being connected with the shaft 13 of the motor by 80 sprocket and chain or similar engagement, as indicated at 23. The bearings 20 and 17 of the connecting rods may be lubricated in any desired manner, the former being preferably provided with hard grease cups indicated at 24, and the latter having formed therein oil holes 25 by means of which oil 85 may be introduced to the grooves 15. 90

Mounted upon a bushing 26 carried by one end of the shaft 22 is a padded wheel 27, 100 and upon the opposite end of the shaft 22 is secured for rotation with the shaft, a sanding wheel 28 having any suitable means, as at 29, whereby the sandpaper may be secured thereto. Secured to the forward end 105 of the adjacent connecting rod 18 is a strap iron frame or guard 30 surrounding the sanding roller and maintaining the same at all times in spaced relation to the base board against which it is operating so that it will 110 not damage the base board but at the same time permitting the roller to come close

enough to the base board to leave only a strip unsanded which may be covered by the ogee molding above mentioned. An operating handle 31 is provided secured at its 5 lower end, as by means of straps 32, to the housing 21 and having at its upper end a cross bar to be engaged by the hands of the operator. Adjacent this cross bar the operating handle is provided with a switch 33 10 controlling the motor.

In the use of my device in sanding, the operator having started the motor, moves the machine with the sanding roller and guard against the base board or in close proximity 15 thereto along one side of the room, the machine being for example in the position shown in Figure 3. Arriving at this corner and desiring to change the position of the machine so that it may reach into a corner 20 which must be approached from the left hand, the operator elevates, through medium of the handle 31, the free ends of the connecting rods 18, these rods rotating about the bushings carried by the hub portions of 25 the motor housing and permitting the entire machine to be reversed. With the machine so reversed, it will be obvious that the left hand corner may be sanded by the use of the roller with the same facility that is met 30 with in sanding the right hand corner.

It will be obvious that by the use of a ma-

chine of this construction, the necessity for scraping the unsanded edges is eliminated and that the amount of work accompanying a given operation is accordingly lessened and 35 a better finish applied to the floor. It will likewise be obvious that the construction of the machine being very simple, the device will be durable in service and capable of 40 continued use without the necessity of replacing delicate parts. I accordingly do not limit myself to the specific structure hereinbefore set forth except as hereinafter 45 claimed.

I claim:—

In a floor sanding device, a wheel supported motor embodying the usual housing and shaft, connecting rods pivotally engaged with the motor housing at opposite sides thereof and rotatable upon the housing 50 with the shaft as a center, a shaft rotatably mounted in the free ends of said connecting rods, a sprocket and chain connection between the motor shaft and the last named shaft, said connecting rods being adjustable 55 as to length, an operating handle rotatably engaged with the last named shaft, and a sanding wheel carried by one end of the last named shaft.

In testimony whereof I hereunto affix my 60 signature.

THOMAS G. HOLT.
